UNITED STATES PATENT OFFICE.

GEORGE H. FAICHNEY, OF WATERTOWN, NEW YORK, ASSIGNOR TO THE RANDALL-FAICHNEY COMPANY, OF BOSTON, MASSACHUSETTS, A CORPORATION OF MASSACHUSETTS.

MULTIPLE-ENGRAVING MACHINE.

1,359,242.

Specification of Letters Patent. Patented Nov. 16, 1920.

Application filed January 2, 1920. Serial No. 349,115.

To all whom it may concern:

Be it known that I, GEORGE H. FAICHNEY, a citizen of the United States, residing at Watertown, in the county of Jefferson and State of New York, have invented certain new and useful Improvements in Multiple-Engraving Machines, of which the following is a specification.

This invention relates to improvements in multiple engraving machines, and has for its object to provide a novel, simple and inexpensive mechanism, whereby a plurality of articles of different size and shape may be simultaneously engraved with the same characters, and whereby the construction, arrangement and operation of the machine is such that but a single operator is required to operate it. A further object is to provide a multiple engraving machine wherein a plurality of gravitational engraving tools are arranged in pairs, and each pair is controlled in its vertical movements by an arm which is connected to and partially revoluble around the axis of a rocking-bar, the arrangement of said arms being such that a number of them are secured to and actuated by the same rocking bar. A further object is to provide means for simultaneously releasing all of the engraving tools so as to allow them to gravitate to the engraving positions, and also means for simultaneously releasing and withholding all of the tools while the work is being changed. A further object is to provide means for moving all of the tools in a common horizontal plane during the engraving operations. And a further object is to provide means for operatively connecting the machine with a pantographic mechanism, which effects and controls the movements of the machine during the reproduction of the characters from a common copy.

The various features and parts of the invention will be understood from the detailed description which follows, and by reference to the accompanying drawings, in which—

Figure 1 is a top-plan view of the complete machine. Fig. 2 is a front side elevation of the same. Fig. 3 is a front end elevation of the machine. Fig. 4 is an enlarged elevational view of one pair of the

engraving tools, their supports, and the means for controlling the vertical movements of said tools, relatively to the work to be engraved. Fig. 5 is a top-plan view 55 of the same. Fig. 6 is an enlarged detail view of one of the arms which prevents or permits the gravitation of the tools. And Fig. 7 is a broken detail view; showing the manner of pivotally connecting the tracer 60 arm with the oscillating lever of the pantograph.

In the drawings, 2 designates the base which supports the movable and stationary parts of the machine, the former consisting 65 of one frame 3, the latter comprising two independent frames 4 and 5. The frame 4 comprises a number of posts 4', which are rigid on the base, and which mark the four corners of the frame, the corresponding 70 posts supporting transverse bars 4^a, which are secured rigidly to the posts by screws 4^b. The facing edges of the bars 4^a are rabbeted to receive a horizontal platform 4^c, which is adjustable on the guides 4^a by 75 screws 4^d. The opposite longitudinal edges of said platform is provided with cleats 4^e, that serve to retain a work-supporting table 4^f, which is removable for loading and unloading the work or articles C to be engraved. The table 4^f is adjustable longitudinally and horizontally on the platform 4^c, as shown by dotted lines in Fig. 2, for positioning the work C relatively to the engraving tools. The frame 5 comprises 80 similar relatively tall columns or posts 6, which are rigid on the base 2, and are spaced a considerable distance to the right and the left of the bars 4^a. The tops of the columns 6 are tied together by a longitudinally disposed rail 6' which parallels the base, and these parts are held rigidly by similar braces 6^a, which are secured respectively to the ends of the rail 6' and to the base 2. The movable frame 3 comprises a 85 horizontal platform 7, which is disposed beneath and parallel to the platform 4^c and the table 4^f, and is rigidly mounted on the tops of similar spaced and grooved bearing members 8, the said members in turn being 90 supported and movable longitudinally on similar members 8', by means of a plurality

- of balls 8^a, which play in the facing grooves of the said members. The bearing members 8' are rigidly secured to the tops of transverse bearing members 9, which are movably supported on similar members 9', by means of balls 9^a, which play in the facing grooves of the latter members. The bearing members 9' are rigidly secured to the base 2, and are therefore normally stationary.
- 10 Across the opposite ends of the platform 7 are rigidly mounted relatively deep cleats 7', upon which are mounted horizontal and longitudinal bars 10, which are held by the said cleats above and clear of the work C on the table 4^r. The table 4^r is preferably provided with a number of longitudinal grooves c' in which the work C is received and held during the engraving operations, and the bars 10 are preferably disposed between said grooves.
- 15 The engraving is effected on a number of the articles C in the same time by a plurality of similar engraving tools or needles 11, which are supported by the bars 10, and preferably arranged in pairs, and so arranged that the points of the said needles are always maintained in a common horizontal plane. The needles 11 depend from the lower ends of cylindrical plungers 12, which are reciprocably and rotatably held by vertical sleeve-like arms 13' of L-shaped brackets 13, the horizontal arms 13' of said brackets being disposed beneath and adjustably secured to the bars 10, by bolts 13^a.
- 20 The top ends of the plungers 12 are provided with horizontally disposed fingers 12', which are employed for lifting and holding the plungers away from the work C. The vertical movements of the plungers 12 are controlled by a plurality of arms 14, there being one of said arms for each pair of the plungers, the said arms preferably being disposed transversely of the bars 10 and their free ends being positioned between the adjacent plungers 12. Each arm 14 is provided near its free end with a U-shaped guard 14', between the vertical arms of which the fingers 12' are disposed, and these guards are so arranged as to allow the plungers 12 a certain amount of rotary movement, as may be understood by the different positions of the fingers, in Figs. 1 and 5. The other ends of the arms 14 are rigidly secured to rocking shafts 15, which extend longitudinally across the machine, the said rocking shafts being journaled in transverse rails 16 which are supported by the cleats 7'. The corresponding ends of the rocking shafts 15 are fitted with wheels 15', which are connected for simultaneous rotation in one direction by a rod 15^a. The shafts 15 are rotated in the opposite direction by a cord 17, which is connected to the periphery of one of the wheels and extends
- 25 downwardly through the platform 7 and the

base 2, and connects with a pedal (not shown). A spring 18 connects at one end to the rod 15^a, the other end thereof connecting to the adjacent cleat 7'. The tension of the spring 18 is exerted for holding the arms 14 and the plungers 12 in their elevated positions, shown in full lines in Figs. 2, 3 and 4, which is the released or idle position for the needles 11.

All of the parts supported by the cleats 7', including the gravitational needles 11 and their related and controlling parts are movable by and with the movable frame 3, and all of these parts in turn are moved and guided and controlled by a simple pantograph mechanism, which will now be described.

19 designates the tracer arm or lever, which is manipulated by the operator, the said arm being disposed horizontally beneath the several frames, and its forward end is fitted with the tracing needle or point 19', which the operator moves over the copy A during the engraving operations. The rear end of the arm 19 is pivotally connected to a vertically disposed lever 20, the top end of which is pivoted in a horizontal frame 21, by a bolt 20'. The frame 21 is suspended on a bolt 22 which is carried by the middle portion of the rail 6', the said frame being rockable on said bolt by pivots 21^a, as shown by dotted lines in Fig. 2. The upright lever 20 is operatively connected to the movable frame 3 by a substantially horizontal rod 23, the rear end of said rod comprising a yoke 23', which is pivoted to the lever 20 below the pivot 20'. The forward end of rod 23 is pivoted at 23^a to an upright standard 24, which is mounted on the rail 10 nearest the front of the machine. The pivot point 23^a is adjustable vertically on the standard 24 by means of a bolt 25, which plays in a slot 25' in the standard, for varying the movements of the frame 3. The pantograph mechanism is adjustable in various ways which are not shown, because they are well-known and are not important in the present case, since any suitable mechanism of the class may be employed in connection with my improvement.

The operation of the present machine, is as follows: Assuming that the work-table 4^r has been loaded with the work C, and placed in the machine, the operator depresses the pedal (not shown) for pulling downwardly on the cord 17. This partially rotates the wheels 15' against the tension of the spring 18, and rocks the shafts 15 in the direction for moving the arms 14 from the full to the dotted line position shown in Figs. 2, 3 and 4. This depressing of the arms 14 frees the plungers 12, so that they instantly gravitate until the needles 11 make contact simultaneously with the work C (see dotted lines in Figs. 2 and 4). The operator maintains

the pressure on the pedal, while he traces the copy A with the point 19'. As the point 19' follows the outlines of the letters and other characters of the copy A, the levers 19 and 20 are put through the several motions indicated by the full and dotted lines in the several figures of the drawings. This, owing to the connection of the lever 20 through the rod 23, with the movable frame 3, im-
parts to the said frame forward, backward and circular movements necessary to effect the reproduction of the characters of the copy A on the work C by the needles 11, as best seen in Fig. 1. When the operator has finished tracing the copy A, the pull on the cord 17 is relaxed and the spring 18 instantly rocks the shafts 15 in the opposite direction, which shifts the arms 14 from the dotted back to the full line position (see Fig. 4) and lifts all of the plungers 12 and needles 11 upwardly away from the work C, where they are held by the spring 18 ready for the next engraving operation. The reproduction in the present case is on a greatly reduced scale, so that the movements of the frame 3 and the parts supported by it are very slight.

My engraving machine is extremely simple in construction and operation, and may be produced at slight expense. It is capable of performing rapid and accurate work, and by the novel disposition and arrangement of the several gravitational needles 11, the capacity of the present machine is many times greater than the older styles of engravers, which as a rule engrave but one article at a time.

Having thus described my invention, what I claim as new and desire to secure by Letters Patent, is—

1. In a multiple engraving machine, a stationary horizontal work-supporting table, a frame adapted for horizontal movements disposed beneath said table, cleats carried by said frame for elevating above said table a plurality of gravitational tools, said tools arranged in pairs, fingers carried by said tools, a rocking-arm for each pair of tools having guards adapted to receive the fingers of said tools, shafts for supporting and operating said arms, means for depressing said arm for permitting said tools to gravitate toward said table, means for raising said arms for lifting said tools away from said table, and means for actuating said frame.

2. In a multiple engraving machine, a frame adapted for universal movements in a horizontal plane, a plurality of gravitational engraving needles arranged in pairs supported and moved horizontally by said frame, arms having U-shaped guards adapted for normally holding said needles away from the work, one of said arms disposed between

and controlling each pair of said needles, 65 shafts supporting said arms, tension means for rocking said shafts in one direction and for holding said arms elevated, and means for rocking said shafts against the tension for depressing said arms and for permitting 70 said needles to simultaneously gravitate to the engraving position, a work-supporting table disposed beneath the needles, and means for actuating said frame.

3. In a multiple engraving machine, a 75 work-supporting table, means for adjusting said table, a movable frame including a platform disposed beneath said table, horizontal bars supported by said platform above and parallel to said table, rock-shafts 80 disposed in a higher plane than said bars, cleats upon the frame for elevating the bars and rock shafts above the table, a plurality of arms carried by each shaft, their free ends overlapping said bars, U-shaped guards 85 carried by said arms, a plurality of gravitational engraving tools mounted on said bars, said tools arranged in pairs and having fingers which engage said guards, means for rocking said arms in the direction for allowing said tools to gravitate toward said table, and tension means for rocking said arms in the opposite direction for lifting said tools away from the table.

4. In a multiple engraver, a frame adapt- 95 ed for universal movements in a horizontal plane, a stationary frame for adjustably supporting work to be engraved, a platform included in the movable frame disposed beneath the work-supporting parts, cleats 100 mounted near the ends of said platform, horizontal bars supported by said cleats, a plurality of gravitational engraving tools ad- justably mounted on said bars, said tools ar- ranged in pairs, rocking shafts disposed 105 above and parallel to said bars, arms carried by said shafts, the free ends of said arms disposed between each pair of engraving tools and provided with guards, fingers carried by said tools and adapted to rest on 110 said guards while the tools are idle, and means for rocking said shafts for lowering said guards and allowing said tools to gravitate toward the work.

5. In a multiple engraving machine, a 115 plurality of gravitational engraving needles arranged in pairs, plungers supporting said needles and movable vertically, a finger carried by each plunger, a bracket support- 120 ing each plunger, horizontal bars support- ing said brackets and maintaining the points of said needles in a common horizontal plane, a work-supporting table disposed beneath the said needles, a movable frame sup- porting and actuating said needles during 125 the engraving operations, said frame adapt- ed for universal movements in a horizontal plane, rocking shafts journaled in said

frame, arms carried by said shafts, the free end of each arm disposed between a pair of said plungers and having a guard adapted to engage the fingers of said plungers for lifting said plungers away from the work after the engraving operations, means for operating said arms for allowing said

plungers to gravitate toward the work, a plurality of ball-bearings on which said frame is held by gravity and is guided in a horizontal plane, and a tracer arm adapted for actuating said frame.

In testimony whereof I affix my signature.

GEORGE H. FAICHNEY.
